(57) **CLAIM**

The ornamental design for a clip for a lid of a container, as shown and described.

DESCRIPTION

FIG. 1 is a perspective view of a clip for a lid of a container; FIG. 2 is a top view of the clip of FIG. 1; FIG. 3 is a bottom view of the clip of FIG. 1; FIG. 4 is a front view of the clip of FIG. 1; FIG. 5 is a rear view of the clip of FIG. 1, in which the unclaimed portion of the lid is seen; FIG. 6 is a left view of the clip of FIG. 1; and, FIG. 7 is a right view of the clip of FIG. 1. The broken lines in the drawings represent unclaimed environmental subject matter and form no part of the claim.
